UNITED STATES PATENT OFFICE.

JAMES WILLIAM GREEN, OF PORTLAND, OREGON.

ROTARY GAS-ENGINE.

1,305,966.

Specification of Letters Patent. Patented June 3, 1919.

Application filed December 22, 1916. Serial No. 138,397.

To all whom it may concern:

Be it known that I, JAMES WILLIAM GREEN, a citizen of the United States, residing in the city of Portland, county of Multnomah, and State of Oregon, have invented certain new and useful Improvements in Rotary Gas-Engines, of which the following is a specification.

My invention relates to rotary gas engines, and it has among its salient objects to provide an internal combustion engine in which are a plurality of revolving rotors, or vanes adapted to be intermittently and alternately driven forwardly, and also to 10 be intermittently and alternately locked against backward movement, whereby to form an abutment between which, and the rotor, or vane, next to be moved, the explosion takes place and drives the movable rotor, or vane, forwardly a partial rotation. Said latter vane, or rotor, is then locked against backward movement and it becomes the abutment between which, and said first rotor, or vane, another explosion takes place 20 and drives said first rotor forwardly a partial turn. Another object of my invention is to provide in a device of the character referred to a construction in which the intake of the explosion mixture, the compression, the ignition, or spark, and the exhaust are automatically controlled by the revolutions of the rotors, or vanes, and can take 30 place at any point around the arc of a circle.

In order that others may understand my invention I have illustrated one practical form thereof in the accompanying sheet of drawings in which,—

Figure 1 is a longitudinal vertical sectional view through my invention;

Fig. 2 is a vertical cross sectional view 40 taken on line 2—2 of Fig. 1;

Fig. 3 is a vertical cross sectional view taken on line 3—3 of Fig. 1;

Fig. 4 is a vertical cross sectional view 45 taken on line 4—4 of Fig. 1;

Fig. 5 is a vertical cross sectional view taken on line 5—5 of Fig. 1;

Fig. 6 is a top plan view of the embodiment of my invention, as here shown for 50 purposes of illustration;

Fig. 7 is a vertical cross sectional view taken through the rotor casing, on line 7—7 of Fig. 1;

Fig. 8 is a side elevation of one of the 55 rotors, or vanes, of my invention;

Fig. 9 is an end view thereof;

Fig. 10 is a side elevation of an apertured bearing sleeve, which fits over the right-hand end portion of the rotor shown in Fig. 8;

Fig. 11 is a vertical cross sectional view taken on line 11—11 of Fig. 10;

Fig. 12 is a side elevation partly in section of the exhaust valve mechanism;

Fig. 13 is a fragmentary top plan view 65 thereof;

Fig. 14 is a face view of the base thereof, with the mechanism removed therefrom;

Fig. 15 is a side elevation of another rotor, or vane, with the upper portion shown in 70 section;

Fig. 16 is an end view of said rotor.

Fig. 17 is an end view taken on lines 17—17 of Fig. 1, showing two traveling contact members which control the sparks; and 75

Fig. 18 is a similar view taken on line 18—18 of Fig. 1, showing two coöperating contact devices.

Figs. 19, 20, 21 and 22 are diagrammatic illustrations, showing in a general way, a 80 cycle of operation; that is,—

Fig. 19 shows the relative positions in the rotor cylinder of the intake, the compression, the explosion and the exhaust, while Figs. 20, 21 and 22 show the same 85 successively changed relative positions of these functions.

In my invention, as here illustrated, I have shown two rotors, or vanes, arranged crosswise of each other, X-fashion, and turning about a common axis, said rotors, or vanes, being notched at their central portions, however, so as to interfere with each other, whereby their vane portions come together flatwise at diametrically opposite 95 sides of their centers. I have also made provision for automatically locking each of said rotors, or vanes, against backward movement, and in the present embodiment of the invention this means for so locking said rotors, or vanes, is accomplished through the hub, or sleeve, portions. I have also provided the intake and exhaust ports through the hub, or middle portion of one of said 100 rotors, and to this end the hub, or body portion thereof, is chambered, as hereinafter described, to provide the necessary intake and exhaust ports, with proper connections for taking in the explosive mixture at any point of rotation of said rotors, through any 105 one of said ports, and afterward exhausting the burnt gases therefrom through the same

port. In other words, there are four ports, all operating the same. Each port serves as an intake port, is closed during compression and explosion and is then opened as an exhaust port, and then as an intake port.

I will now describe in detail the embodiment of my invention, as here illustrated on the accompanying three sheets of drawings.

- Referring to Figs. 1, 6 and 7, 1 designates 10 a drum-like casing having formed on one side an annular flange 2. Rotatably mounted within said casing 1, are two rotors, 3 and 4, Figs. 8 and 16, having, respectively, the vane portions 3^a and 3^b, and 4^a and 4^b. Referring more particularly to Figs. 1, 7, 8 and 9, the rotor 3, is shown in side elevation in Fig. 8, and in end elevation in Fig. 9, and is provided with the hub-like extension 3^e, provided with five pairs of expansion 20 rings, as 3^d—3^d. Said hub-like extension is chambered longitudinally at its four quarters, circumferentially, as at 5, 6, 7 and 8, which chambers open out at their right-hand ends, respectively, between the pairs of expansion rings, as at 5^a, 6^a, 7^a and 8^a, and at 25 their opposite ends, said chambers open out adjacent the vane portions 3^a and 3^b, as at 5^b, 6^b, 7^b and 8^b, as clearly shown in Figs. 7 and 8, and also in Fig. 1.
- 30 Said rotor 3 also has a reduced, hub-like extension 3^e, extending out to the left-side of the vanes 3^a and 3^b, as clearly shown in Figs. 1 and 8. The rotor 4 is mounted upon this extension 3^e of the rotor 3, and has an 35 interfitting connection with the rotor 4, whereby the vanes 3^a and 3^b of the rotor 3, and vanes 4^a and 4^b of the rotor 4 are brought into overlapping relationship with each other, or so as to occupy the same path 40 of rotation, that is, the vane portions 3^a and 3^b of the rotor 3, have an extended width which projects over the hub, or body, portion of the rotor 4, and the vane portions 4^a and 4^b of the rotor 4, have a 45 breadth extension which projects over the body, or middle portion of the rotor 3, as will be understood by reference to Figs. 8 and 15. A shaft 10, is extended through the hub, or central portions of the rotors 3 50 and 4, as clearly shown in Figs. 1 and 7, said shaft being provided at one end with an arm 11, keyed thereto, as at 12, and provided with forks 13—13, at its opposite ends adapted to receive the screw bolts 14—14, 55 which are screwed into the body of an eccentric locking device 15, shown in longitudinal section in Fig. 1, and in cross section in Fig. 4, said driving device 15, turning on the extension 3^e, and being secured by means 60 of set screws 16—16, to the hub, or body portion of the rotor 4, whereby said eccentric driving device 15, is secured to and turns with said rotor 4. Mounted on the outer end of the sleeve, or hub-like, extension 3^e, 65 of the rotor 3, is an irregular eccentric driv-

ing device 17, shown in section in Fig. 1, and in end elevation in Fig. 3, said device 17 having neck-like portions 17^a—17^a, which support the eccentric cam devices 17^b—17^b, as clearly seen in Fig. 3, it being understood 70 that the screw bolts 14—14, extend along adjacent the neck portions 17^a—17^a, of said driving device 17, whereby the latter can only turn a partial revolution at a time, in the direction of the dotted line arrow, Fig. 75 3, after the arm 11, together with the screw-bolts 14—14 and the member 15, have been turned a partial revolution. A pair of locking or holding rollers 18—18, is mounted 80 between the eccentric cam faces 15^a—15^a, of the member 15, and the flange 2, on the side of the rotor casing 1, as will be seen in Fig. 1. A main driving shaft 19, is provided with a drum, or bell, portion 20, of substantially the same diameter as is the annular 85 flange 2, on the side of the rotor casing 1, and is placed over and around, so as to enclose the end of the shaft 10, the arm 11, and the devices 15 and 17, and forms, as it were, an extension of said annular flange 2, 90 as will be clearly understood from Figs. 1 and 6. Also mounted between the eccentric cam faces 15^a—15^a of the member 15, is a pair of driving rollers 21—21, normally 95 pressed outwardly by means of spring-pressed plungers 22—22, as clearly shown in Fig. 4, whereby when said device 15, is driven in one direction it will be locked to and drive said bell or drum 20, but will be free to turn in the opposite direction without turning said drum or bell 20 on the shaft 19. Mounted between the eccentric cam faces 17^b—17^b, of the member 17, and the inside of said bell, or drum, 20, is a pair of 100 driving rollers 23—23, also normally held in locking position by means of spring-pressed plungers 23'—23', as will be clearly seen from Fig. 3. Thus by means of the rollers 23—23, the driving device 17, secured to the extension 3^e, of the rotor 3, makes it possible 110 to lock the bell or drum 20, of the main driving shaft 19 to said rotor 3 for intermittently driving said bell 20 and its shaft 19 in one direction, while the rollers 21—21, between said bell or drum 20, and the driving member 15, secured to the hub of the rotor 4, makes it possible to lock said rotor 4, to said drum or bell 20 for intermittently driving it and its shaft 19 in the same direction. The holding rollers 18—18, operating 120 between the annular flange 2, on the casing 1, and said member 15, which is secured to the rotor 4, operates to lock said rotor against any backward movement. The rotor 3 is similarly locked against any backward 125 movement or rotation by means of a pair of similar holding rollers 24—24, operating on the opposite end of its hub or extension 3^e. To this end there is keyed, as at 27, to the end of said extension 3^e, an eccentric locking 130

device 25, similar to the device 15, shown in Fig. 4, and having similar eccentric cam faces between which and an annular ring, or collar 26, secured to the casing, hereininafter referred to, said rollers 24—24, operating to lock said rotor 3, against any backward movement.

Mounted at the side of the rotor casing 1, around the extension 3^c of the rotor 3, is a cylindrical casing 30, shown in section, Fig. 2, and adapted to be secured to the side of the rotor casing 1, as by means of bolts 31—31, said cylinder casing 30, having formed therein a series of annular spaced chambers, as 32, 33, 34 and 35. Mounted within said cylindrical chamber is a cylindrical skeleton, or apertured bearing sleeve 36, shown in side and sectional views in Figs. 10 and 11, the apertures in said bearing sleeve extending circumferentially therein and being spaced apart so as to register with the annular chambers 32, 33, 34 and 35 in said cylindrical casing 30, as will be clear from Fig. 1. Said apertured sleeve, as will be noticed, fits closely around the extension 3^c of the rotor 3, and the expansion rings 3^d thereon, the apertures in said bearing sleeve registering with the spaces between the pairs of extension rings. Thus it will be understood that the different chambers 5, 6, 7 and 8, in the extension 3^c of the rotor 3, open at their ends 5^a, 6^a, 7^a and 8^a, respectively, through the apertures in the bearing sleeve 36, and into the annular chambers 35, 34, 33 and 32, in the cylindrical casing 30. In Fig. 2, the chamber 5, in said extension 3^c, is shown with its opening 5^a opening through the apertured ring 36, into the annular chamber 35. Said cylindrical casing 30, is provided at one side with a flat flange-like face 30^a, to which is adapted to be attached the exhaust valve mechanism, shown in Figs. 12, 13 and 14, and hereinafter again referred to. The annular chambers 32, 33, 34 and 35, in said cylindrical casing, have outlet ports through said flange or face 30^a, Fig. 2, which outlet ports are designated 32^a, 33^a, 34^a and 35^a, the outlet port 35^a, being shown in full lines in said Fig. 2, while the other outlet ports are indicated in dotted lines. Secured flatwise to said flange, or face, 30^a, is the exhaust valve mechanism, shown in Figs. 12 and 13, said exhaust valve mechanism being shown in place in top plan view in Fig. 6, and comprising a base plate 40, having the bolt holes 40^a—40^b, therein, to receive the screw bolts 40^b—40^b, Fig. 12. Said base plate also has four exhaust apertures therethrough, which correspond and register with the exhaust apertures 32^a, 33^a, 34^a and 35^a, through said flange face 30^a, to which said base plate is connected. I have, therefore, designated the exhaust apertures 65 through said plate with the same reference

numerals, as they are continuations of the same apertures when said base plate 40, is secured flatwise on to the flange face 30^a. Secured on to the face of said base plate 40, as shown in Fig. 14, in communication with the exhaust apertures therethrough, is a box-like casing within which are mounted four valve members, designated 41, 42, 43 and a fourth one, 44, (not shown), but which is in connection with the exhaust opening 33^a indicated in dotted lines in said Fig. 12. These valves 41, 42 and 43, and 44 control, respectively, the exhaust outlets through the exhaust apertures 35^a, 34^a, 32^a and 33^a, into a common exhaust chamber, 45, from which is an outlet opening formed by the extension 46, as shown in Figs. 12 and 13. Said valves 41, 42, 43 and 44, are mounted on piston rods 41^a, 42^a, 43^a and 44^a (not shown), connected with pistons 41^b, 42^b (not shown), 43^b and 44^b, working in small cylinders 41^c, 42^c (not shown), 43^c and 44^c. Said piston rods 41^a, 42^a, 43^a and 44^a, extend in a reduced size through said valves 41, 42, 43 and 44, and out through packing nuts 47, 48, 49 and 50, and are normally pressed inwardly, whereby to seat said valves, by springs 51, 52, 53 and 54, on the nuts 40^b.

Thus it will be understood, for example, that any explosion through one of the exhaust ports 32^a, 33^a, 34^a or 35^a, above the valve adjacent thereto, will force the piston, which is adjacent thereto, and whose cylinder communicates therewith, so as to open the next valve in order, against the tension of its spring, thus allowing the burnt gases from the previous explosion to be exhausted through said exhaust port into said general chamber 45, and out through the outlet 46. To be more specific, any explosion through the exhaust port 35^a, above valve 41, Fig. 12, will force piston 43^b, so as to open valve 43, against the tension of its spring 53, and allow burnt gases to be exhausted through exhaust opening 32^a, and into the general chamber 45.

Referring now to Figs. 2 and 6, there is mounted upon the top of the cylindrical casing 30, by means of the bolts 60—60, a box-like member 61, forming an inlet chamber 62, into which is provided a general inlet indicated at 63. Spring-closed valve and valve stems, designated in a general way 64, 65, 66 and 67, control the communication from the inlet chamber 62, to the respective annular chambers 35, 34, 33 and 32, of the cylindrical casing 30. The general construction and arrangement of these respective valves 64, 65, 66 and 67 is clearly shown in the sectional view, Fig. 1, and need not be described more in detail. It will thus be understood that a supply of explosive mixture connected to the general inlet 63, passes into the general chamber 62, in the

box 61, and as suction is applied through any of the passage chambers 5, 6, 7 and 8, extending through the rotor extension 3^c, respectively, to the annular chambers 35, 34, 5 33, and 32, that said valves 64, 65, 66 and 67 will yield.

Also mounted in the top of the cylindrical casing 30, and above the respective annular chambers 35, 34, 33 and 32, are spark plugs 10 70, 71, 72 and 73, shown in top plan view in Fig. 6, in which figure also it is shown that said spark plugs are electrically connected in pairs, spark plugs 70 and 72 being connected together to wire 74, so as to spark 15 at the same time, and spark plugs 71 and 73 being electrically connected together by the wire 75, to spark at the same time, said wires 74 and 75 leading to and connecting, respectively, with contact rings 76 and 77. 20 The contact rings 76 and 77 are supported at a space apart upon sleeves 78 and 79, of insulating material upon bolts 80 and 81, which are secured to a ring 82, attached to the member 25, keyed to the end of the hub 25 extension 3^c, of the rotor 3, whereby said contact rings 76 and 77, revolve with said rotor. Two contact members, or prongs, 83 and 84, are carried by said contact rings 76 and 77 contact member 83 being connected 30 to contact ring 76, and being insulated from ring 77, although passing through the same, while contact member 84 is attached directly to contact ring 77. Secured to the shaft 10, opposite the contact rings 76 and 77, is a disk-like member 85, to the face of which is bolted at a space therefrom, a contact ring 86. Spacing sleeves 87-87, of insulating material holds said contact ring 86, insulated from the disk 85. Secured to the face 40 of said contact ring 86, are two spring contact members 88 and 89, shown also in face view of Fig. 18, said contact members 88 and 89, being adapted to intermittently contact, respectively, with the contact members 45 83 and 84, as said contact rings 77 and 76, and the contact ring 86 are intermittently revolved. It will be noted that the contact ring 86, being secured to the disk 85, which is keyed to the shaft 10, as at 85^a, turns with 50 said shaft, and as said shaft, at its opposite end, is connected through the parts 11, 14, 15 and 16, to the hub of the rotor 4, contact members 88 and 89 revolve with rotor 4, while the contact members 83 and 84, revolve with the rotor 3. A source of electricity is connected in any desirable way, as through a wire 90, with the contact ring 86.

I will next describe a starting mechanism for starting our engine, which will be under- 60 stood by reference to Figs. 1 and 5.

Mounted over the disk 85, which is keyed to the shaft 10, Fig. 1, is a gear 91, provided with an annular flange, as 93, having eccentrically disposed run-ways 93, arranged 65 circumferentially thereof, and between which

run-ways and the disk 85, is a series of locking balls 94, whereby as said gear 91, is turned in one direction, as indicated by the arrow, Fig. 5, it will be locked to and turn the disk 85, together with its contact ring 70 86. Said gear 91, however, can be turned in the opposite direction loosely, without turning the disk 85, and the shaft 10, to which it is keyed. Mounted on the annular ring, or collar 26, and the member 25, is another gear ring, or rim, 95, having formed on its inner face a series of eccentrically disposed runways, similar to the run-ways 93, shown in Fig. 5. Between said gear ring 95, and the members 25 and 26, are two series of 80 balls 96, and 96^a, as clearly shown in Fig. 1, the larger ones 96, being locking balls and operate in exactly the same manner as do the locking balls 94, shown in Fig. 5. The series of balls 96^a form a bearing between the 85 parts 26 and 95.

Mounted in a suitable bearing block 97, is a short shaft 98, to the outer end of which, as at 99, may be attached any means for applying power. Mounted on said shaft near 90 its opposite ends are two gears 100 and 101, which mesh, respectively, with the gears 91 and 95. Said gears 100 and 101 are formed with hollow inner adjacent faces, and are provided therein, keyed to said shaft 98, 95 as at 102-102, with disk-like members 103-103, provided around their outer edges with a plurality of spacing sleeves 104-104, to which are attached rings 105-105. An internal driving tooth, or lug, as 106, is 100 formed on the inner side of each of the gears 100 and 101 as shown in Fig. 5, adapted to be engaged by a pawl, or dog, as 107, one of which is pivotally secured to each of the disks 103-103, as between the disk 103 105 and its ring 105. The inner ends of said pawls, or dogs, 107, ride upon the projecting opposite end portions of the bearing block 97, which opposite ends are formed into flangelike extensions, as 97^a-97^a, which 110 overlie the hub portions of the disks 103-103, as clearly shown in Fig. 1. Said flange-like extensions 97^a-97^a, of said bearing block 97, are cut away, as at 97^b, for a portion of the circumference thereof, whereby when the inner end of the pawl, or disk, 107, reaches this cut-away portion 97^b, it is free to swing and automatically disengages from the driving tooth, or lug, 106, on the inner face of the gear 100. These 120 cut-out portions 97^b, at the opposite ends of the bearing block 97, are at different positions circumferentially, so that when the starting shaft 98, is turned, one of the gears, as 100, will be locked to said shaft through 125 the disk 103, the pawl 107, and the driving tooth 106, and will drive gear 91, turning the shaft 10 above, which in turn drives the rotor 4. By the time the pawl, or dog, 107, reaches the cut-away portion 97^b, it swings 130

free of the driving tooth, or lug, 106, on the free gear 100, and by this time the corresponding pawl, or dog, 107, on the disk 103, in gear 101, engages a corresponding driving tooth, or lug, 106, in said gear 101, whereupon by the continual movement of shaft 98, in the same direction drives gear 101 a partial rotation, and through its connections with gear ring, or rim, 95, and the part 25, drives the rotor 3 a partial rotation. Thus continual turning of the starting shaft 98, alternately drives gear 91 and gear ring 95, each a partial rotation, and through their connections alternately turns the rotors 3 and 4 partial rotations.

The operation of my invention may be briefly described as follows:

Referring to Figs. 19, 20, 21 and 22, I have illustrated in a general diagrammatic manner one cycle of the operations; that is, in one quarter, or section, of the rotor casing, as the rotor vanes are alternately and intermittently moved, the explosive mixture is being taken in; in the first preceding quarter, a charge of explosive mixture is being compressed; in the second preceding quarter the explosion of another charge is taking place, and in the last preceding quarter, the exhaust is taking place. It will be noticed that this order of functions steps backwardly substantially one quarter each time; that is, the intake is one step back, in Fig. 20, of its position as shown in Fig. 19. In Fig. 21, it is a further step back, and in Fig. 22, it is a still further step back. In the next action it would be again substantially in the position of the intake, Fig. 19. It will be understood, of course, that these figures do not always represent the exact positions at which the functions—the intake, the compression, the explosion and the exhaust take place each time, for the rotors are revolving and there can be and is a general shifting, it being understood that the intake may take place at any point around the arc of the circle, as may also the compression, the explosion and the exhaust.

50 Referring now to Fig. 7, we will assume that a charge of gas has just been compressed between rotor vanes 3^a and 4^a , and that an explosion is taking place. Rotor vane 3^a , is locked against backward movement while rotor vane 4^a , will be driven forwardly, and will exhaust the burnt gases 55 ahead of it through the chamber outlet 5. The rotor vane 4^b , will compress a charge of gas ahead of it as it approaches rotor vane 3^a , and moves into the position shown in dotted lines, and at the same time it will 60 draw in a charge through chamber 7, in its rear. As the rotor vane 4^b approaches the rotor vane 3^a above, as shown in dotted lines, compressing the charge therebetween, another explosion takes place which drives the 65 rotor 3 forwardly, its vane 3^a , having re-

ceived the impulse from the explosion, is driven forwardly and forces out the burnt gases ahead of it, while its rotor vane 3^a is compressing a charge in front of it, and is drawing in a fresh charge in its rear. 70 Thus the operation is repeated continuously, the position of the explosion being one step back each time, as is illustrated in the dia-grammatic Figs. 19 to 22.

grammatic Figs. 19 to 22. It will be understood, of course, from the detailed description, that the contact members of the sparking mechanism travel with the rotors, and that they can be so adjusted that as the rotor vanes approach each other, the spark takes place therebetween, no matter at what position in the rotor casing they may be. It will also be understood that the passageways from the general supply chamber 60, through the annular chambers 32, 33, 34 and 35, and through the different chambers 5, 6, 7 and 8, in the rotor extension 3^c, to the rotor casing, are automatically closed by the valves 64, 65, 66 and 67, excepting when there is an intake suction applied through any one of these passageways to the general supply chamber 62, sufficient to open its particular valve. It will also be understood that these passageways are also automatically and successively opened through the exhaust valve mechanism, it having been shown how the force of an explosion in one of the chambers, as through 35^a, Fig. 12, moves piston 43^b and opens valve 43 for exhaust through 32^a into 45, and out through 46, thus each explosion opens the exhaust valve to a preceding chamber in which an explosion has taken place, whereby the burnt gases are forced out of the different chambers in successive order.

bers in successive order. Thus it will be seen from the foregoing description of one practical embodiment of my invention, taken in connection with the drawings, that I have produced an improved rotary internal combustion engine, in which the power is applied direct to the driving shaft, without the use of cranks. I have also produced in such an engine a construction in which the intake of the explosive mixture can take place at any point around the arc of the circle, and also a construction in which the exhaust can be made at any point around the arc of the circle. 105 110 115

around the arc of the circle. Attention is also called to the fact that inasmuch as spark plugs 70 and 72 are connected to operate together, as are also spark plugs 71 and 73, two sparks take place at the same time between the opposite ends of the rotor vanes, so that if there is any explosive mixture left between any two of the vanes as they approach each other, it will be exploded at the same time the main charge is exploded between the two opposite rotor vanes. For example, referring to Fig. 7, assuming that a spark is due between rotor vanes 3^a and 4^a, which will drive rotor vane 4^a forwardly

into the dotted line position, there will also be a spark for discharging any explosive mixture which may have remained between rotor vanes 3^b and 4^b , which explosion, if any, would coöperate with the main explosion taking place between rotor vanes 3^a and 4^a . The main explosion would drive the rotor vane 4^a forwardly, while the other explosion, if any, would drive its opposite end, 10 rotor vane 4^b , forwardly.

Attention is also called to the fact that the exhaust valve mechanism, as shown in Figs. 12 and 13, can be detached bodily by simply removing the bolts. This is also true of the 15 intake valve mechanism, the box, or casing, 61, being easily removed by the removal of the screws, or bolts, 60-60.

I am aware that many changes can be made in my invention as here shown and 20 described for purposes of illustration, without departing from the spirit thereof, and I do not, therefore, limit the invention to the embodiment here shown, except as I may be limited by the hereto appended claims.

25 I claim:

1. In a rotary engine, a piston casing, pistons arranged in crossed relationship therein and adapted to move forwardly step by step alternately, means for holding said 30 pistons against backward movement, said pistons having hub portions extending from the sides of said casing, one of said hub portions having combination inlet and exhaust passageways extending longitudinally 35 therethrough from within the casing to a position outside of said casing, and controlling mechanism outside of said casing for controlling the inlet and exhaust action of said engine, substantially as described.
- 40 2. In a rotary engine, a piston casing, a shaft therethrough, pistons in crossed relationship in said casing to turn about the axis of said shaft, said pistons having hub portions in interfiting relationship around 45 said shaft, the hub portion of one of said pistons having longitudinally extending passageways therethrough to the spaces between said pistons, means for automatically holding said pistons against backward 50 movement, said means being outside of said casing, valve mechanism controlling the passageways through the hub portion referred to, and ignition mechanism including rotating contact members, substantially as described.
- 55 3. In a rotary gas engine, in combination, a piston casing, a shaft therethrough, two pairs of pistons mounted thereon in crossed relationship with each other, said pistons 60 having hub portions in interfiting relationship around said shaft whereby said pistons follow each other step by step, the hub portion of one pair of pistons projecting from one side of said casing and the hub portion 65 of the other pair of pistons projecting from

the opposite side of said casing, one of said hub portions having therethrough, longitudinally thereof, a plurality of passageways terminating at their inner ends in said casing between the pistons, and valve controlling mechanism for the outer ends of said passageways outside of said casing. 70

4. In a rotary gas engine, in combination, a piston casing, a shaft therethrough, two pairs of pistons mounted thereon in crossed relationship with each other, one of said pistons having a hub portion extending through the side of said casing and having longitudinally extending ports therethrough terminating at their inner ends within the 80 casing, between the pistons, and at their outer ends outside of said casing, valve mechanism around said hub portion outside of said casing for controlling inlet and exhaust action through said passageways, and 85 ignition means therefor, substantially as described. 75

5. In a rotary internal combustion engine, a casing, two pairs of pistons therein in crossed relationship, said pistons having hub portions, one of which extends through the side of the casing and is provided with a plurality of separate, longitudinally extending passageways terminating at their inner ends within said casing, between the 95 pistons, and at their outer ends outside of said casing, and valve mechanism for controlling said passageways as inlet and exhaust passageways, as said pistons are revolved, substantially as described. 90

6. In a rotary internal combustion engine, a casing, two pairs of pistons in crossed relationship therein, said pistons having hub portions formed to have overlapping interfiting relationship with each other, whereby 105 said pistons follow each other, step by step, one of the hub portions having a plurality of separate passageways extending longitudinally therethrough from outside of said casing to the inside of said casing, and valve 110 mechanism outside of said casing for controlling said passageways as inlet and exhaust passageways. 100

7. In a rotary internal combustion engine, a casing having a shaft therethrough, 115 two pairs of pistons in crossed relationship within said casing said pistons having hub portions formed to have overlapping and interfiting relationship with each other, whereby said pistons follow each other step 120 by step, means for holding said pistons automatically against any backward movement, the hub portion of one pair of said pistons having a plurality of separate passageways longitudinally therethrough from 125 outside of said casing to a point within said casing between said pistons, valve mechanisms around the extended hub portion for controlling said passageways outside of said casing, for inlet and exhaust functions, and 130

ignition means including revolving contact members for said engine, substantially as described.

8. A rotary gas engine of the character referred to comprising in combination a cylindrical casing, a pair of rotors mounted therein to turn about a common axis concentric with said casing, one of said rotors having a hub-like extension provided with a plurality of chambers therethrough and opening into said casing, and the other of said rotors being rotatably mounted in interfitting relationship at its hub-portion with said first rotor, whereby the rotor vanes are in crossed relationship within said casing, a driving member having operating connections with said rotors, means operating to prevent any backward rotative movement of said rotors, means for connecting a supply of explosive mixture through the chambers of said rotor hub extension, with valves for controlling the same, an exhaust valve mechanism connected with said chambers through said hub extension, whereby said chambers act both as exhaust passageways and intake passageways to said rotor casing, and a sparking mechanism controlled by said rotors for igniting the explosive mixture, substantially as described.
9. A rotary gas engine comprising in combination a cylindrical casing, a pair of crossed rotors rotatably mounted therein to turn about a common axis, means for locking said rotors against backward rotative

movement, means providing inlet passageways into said casing through the hub portions of said rotors, means for connecting a supply of explosive mixture to said passageways, whereby the same is drawn into said casing by the rotative movement of said rotors, valve mechanism for controlling the supply of said explosive mixture to said passageways, means for igniting said explosive mixture, said means being controlled by said rotors, and an exhaust valve mechanism connected with said casing, substantially as described.

10. A rotary gas engine comprising in combination a casing, a pair of rotors therein to turn about a common axis, one of said rotors having a hub portion extending through the side of said casing with a plurality of separate, longitudinally extending passageways therethrough from a point outside of said casing to a point inside of said casing, the other of said rotors being rotatable in interfitted relationship at its hub portion with the first rotor, whereby said rotors are in crossed relationship in the casing, and means outside the casing for automatically locking said rotors against backward movement.

Signed at Portland, Multnomah county, Oregon, this 15th day of December, 1916.

JAMES WILLIAM GREEN.

In presence of—

I. M. GRIFFIN,
J. C. STRENG.
